VACUUM CLEANER BRUSH ATTACHMENT OR THE LIKE

George H. Frost, Ashland, Ohio, assignor to Westinghouse
Electric Corporation, a corporation of Pennsylvania

Filed Mar. 25, 1964, Ser. No. 79,184

Term of patent 14 years

(Cl. D9—2)

Fig. 1.

Fig. 4.

Fig. 2.

Fig. 3.

FIG. 2 is a front elevational view of the brush attachment shown in FIG. 1;

FIG. 3 is a side elevational view of the brush attachment shown in FIG. 1; and

FIG. 4 is a rear elevational view of the brush attachment shown in FIG. 1.

The dominant features of my design reside in the portions shown in full lines.

I claim:

The ornamental design for a vacuum cleaner brush attachment or the like, substantially as shown and described.
